W. L. STINE

CONCRETE MIXING MACHINE

Filed July 16, 1925

FIG. 4.

INVENTOR.
30 WALTER L. STINE
BY *Martin P. Smith*
ATTORNEY

UNITED STATES PATENT OFFICE.

WALTER L. STINE, OF LOS ANGELES, CALIFORNIA.

CONCRETE-MIXING MACHINE.

Application filed July 16, 1925. Serial No. 43,980.

My invention relates generally to concrete mixing machines and more particularly to automatically operating valvular means for controlling the volume of the water charges that are delivered to the mixing drum of the machine.

It will be understood that where a relatively large amount of concrete is mixed in batches, for instance, in paving or general building operations, it is always desirable, and in some instances obligatory, that the batch mixtures be uniform, particularly in the water content, and to this end, it is the principal object of my invention, to provide simple, efficient and positively acting valvular means for regulating and making uniform, the water charge volumes that are delivered to the mixing drum with the measured quantities of cement, sand and gravel or the like that make up the batch mixtures.

Further objects of my invention are, to provide a water charge regulating means of the character referred to, that is of strong, rugged structure, capable of being readily installed and used on practically all of the standard forms of concrete mixing machines now in general use, and further, to provide a water charge control valve that is actuated directly from the skip that is utilized for delivering the batch charges of cement, sand and gravel into the mixing drum.

With the foregoing and other objects in view, my invention consists in certain novel features of construction and arrangement of parts that will be hereinafter more fully described and claimed and illustrated in the accompanying drawings in which:

Fig. 1 is an elevational view of a conventional or standard form of concrete mixing machine with parts thereof broken away and in section.

Fig. 2 is a perspective view of the water charge regulating valve and the actuating mechanism therefor.

Fig. 3 is an enlarged detail section taken on the line 3—3 of Fig. 2.

Fig. 4 is an enlarged cross section taken on the line 4—4 of Fig. 2.

Referring by numerals to the accompanying drawings, which illustrate a practical embodiment of my invention 10, 10 designates the frame members of the mixing machine, 11, the traction member, 12 the motor,

preferably, an internal combustion engine, that drives the usual mixing drum 13, 14, the delivery chute into the drum, 15, the skip that hoists and discharges the cement, sand and gravel or the like into said delivery chute, 16 the drum that receives the hoisting cables 17, for the skip, 18 the elevated water supply tank, 19 the supply pipe that delivers water to said tank and 20, the mixed concrete discharge chute.

A predetermined amount of water is maintained in tank 18 by means of a float controlled valve 21 that is located in supply pipe 19 thus producing a practically constant head pressure for the water that is periodically discharged into the mixing drum through the valvular means contemplated by my invention.

Skip 15 is usually provided on its rear side with a fixed arm 22, the outer end of which is pivotally connected to a link 23, and the latter in turn, being pivotally connected to an adjacent member of main frame 10.

The automatic valvular means contemplated by my invention includes a duct, preferably a pipe 24, that leads from the lower portion of tank 18 downwardly to a point above the upper portion of the inlet opening into drum 13, and the lower end of said pipe is provided with a nozzle 25 that is arranged to discharge water through said inlet opening.

Located in a vertical portion of pipe 24 is a globe or gate valve such as 26, having a hand wheel 27, and this valve may be adjusted and set so as to regulate the volume flow of water through pipe 24.

Located in a horizontal portion of pipe 24 is a housing 28 for a gate valve 29, which latter is carried by a short arm 29. This arm is mounted on a shaft 30 having bearing 31 in housing 28, and secured to one end of said shaft outside the housing is the upper end of a depending lever 32. A retractile spring 33 is connected to the intermediate portion of lever 32 and to an adjacent part of frame 10.

Arranged for sliding movement in a suitable bracket 33 that is secured to frame 10 below lever 32 is a rod 34, to which is pivotally connected a spring-held dog or finger 35. This dog is mounted so that it will engage with the lower end of lever 32 and

swing the latter inwardly so as to open valve 29, when rod 34 is moved in one direction and said rod moves in the opposite direction, said dog will strike against the lower end of lever 32, and thereby be depressed so as to pass said lever.

Associated with rod 34 is an expansive coil spring 36 that tends to normally force said rod outwardly to its limit of movement.

Pivotaly mounted on frame 10 below the outer end of rod 34 is a bell crank 37, and the end portion of one arm thereof has a pin and slot connection 38 with the outer end 15 of said rod.

Formed in the outer arm of bell crank 37 is a series of apertures 39, in any one of which may be engaged the upper end of a rod 40, and the lower end of the latter is 20 adapted to be engaged in any one of a series of apertures 41 that are formed in arm 22.

Under normal conditions or while skip 15 is being loaded with the dry material, such as cement, sand, gravel or the like, the various operating parts of the mixer and water control valve occupy the positions as illustrated in Figs. 1 and 2 with dog 35 positioned immediately in front of the lower end of lever 32, and with valve 29 closing 25 the passageway through housing 28, said valve being held in this position under the influence of spring 33.

Valve 26 is manually adjusted and set so as to regulate the volume flow of water 25 through pipe 24 and a practically constant head of water is maintained in tank 18 by the action of float-controlled valve 21.

Motor 12 operates at constant speed, under control of a governor so that the periodic time intervals required for the skip 40 to be elevated into discharging position are uniform.

After the skip 15 receives the proper amounts of dry materials, the operator manipulates the proper control lever or mechanism to cause drums 16 to rotate, thereby winding cables 17 onto said drums, with the result that loaded skip 15 is elevated until it occupies an inclined position with its 50 lower end positioned within and above chute 14, and by gravity, the charge of dry materials will pass from the skip over chute 14 into the mixing drum.

Simultaneous with the upward movement 55 of the skip, bell crank 37 is swung upon its pivot, due to the movement connections 40 and 22, and as a result, rod 34 will be moved inwardly through its bearings 33. As this movement takes place, dog 35 engages the lower end of lever 32, and swings same rearwardly, thereby swinging valve 29 upwardly within its housing and permitting water to discharge through pipe 24 and from nozzle 25 into the mixing drum.

60 Valve 29 will be held open for a fixed or

predetermined time interval, or while lever 32 is engaged by dog 35 during the rearward travel of rod 34 and thus, a given amount of water will discharge into the mixing drum to mix with and moisten the concrete 70 mixture produced therein.

Uniformity of the water charges thus delivered into the mixing drum insures uniformity of "wetness" of the batches mixed in and discharged from the drum and thus 75 uniformity is brought about by the regular time intervals that elapse during the upward swinging movement of the skip, the maintenance of a practically constant head of water in tank 18 and the adjustment of 80 valve 26 that regulates the volume flow of water through pipe 24.

The stroke or travel of rod 34 that carries dog 35, is regulated by adjusting the ends of rod 40 in the apertures in arm 22 and bell crank 37, but in practically all instances, the best results are obtained by making adjustments so that, as the rod travels inwardly, it will carry dog 35 past the end of lever 32, thereby permitting valve 90 29 to close with a quick movement, due to the retractive action of spring 33.

Thus valve 29 always opens and closes at predetermined times in the sequence of operations.

On the outward or return stroke of rod 34, dog 35, in engaging the lower end of the lever 32, is depressed so as to pass said lever and after so doing, it is immediately swung upward so as to be positioned to reengage 100 the lever on the subsequent rearward stroke of the rod.

As heretofore stated motor 12 operates at constant speed under control of a governor so that the speed upward swinging movement of the skip is always the same. Thus, the time periods of inward travel of rod 34 and the open intervals of valve 29 are always the same, thereby producing uniformity of water charges to the batches 110 mixed in drum 13, and consequently insuring uniformity of mixture in a large quantity of concrete that is produced by a batch mixing machine.

The uniformity of mixture is always desirable, particularly when large quantities of batch mixed concrete are used in paving and building operations, and where the machine is used in the production of large quantities of concrete under supervision of 115 an inspector, the adjustable portions of the water control means may be suitably sealed by the person in charge, thereby preventing readjustments by unauthorized persons, and consequent variance of the water charges.

Inasmuch as the delivery of the water charge is automatically effected with my improved apparatus, the operator of the mixing machine is relieved of the time, effort and careful attention usually required 120

to manually open a valve or the like and measure the water charge that enters the mixing drum.

Thus the operator has more time to give 5 to other duties about the mixing machine, and the number of batches mixed per hour or within a given time may be increased.

Thus it will be seen that I have provided 10 a water charge regulating and control device for concrete mixing machines that is relatively simple in construction, capable of being easily and quickly adjusted to suit different conditions, positive and efficient in 15 operation and which may be easily and cheaply produced and installed.

While I have shown and described the preferred embodiment of my invention, it will be understood that various minor changes in the size, form and construction 20 of the various parts of my improved water charge control device, may be made and substituted for those herein shown and described without departing from the spirit of the invention, the scope of which is set forth 25 in the appended claims.

I claim as my invention:

1. The combination with a concrete mixing machine and its charging skip, of a water tank on the upper portion of the machine, means for maintaining a practically constant volume of water within said tank, a pipe leading from said tank for carrying a gravity flow of water into the mixing drum of the machine, and valvular means 30 adapted to be operated by said skip during the greater portion of the charging movement thereof for permitting water to flow through said pipe during the greater part of the charging movement of the skip.

2. The combination with a concrete mixing machine and its charge skip, of a water tank located on the upper portion of the machine, means for maintaining a practically constant volume of water within said 40 tank, a pipe leading from said tank for carrying a gravity flow of water into the mixing drum of said machine, a valve in said pipe and means adapted to be actuated by said skip during the greater portion of the charging movement thereof for opening said valve to permit the flow of water from the tank into the mixing drum during the greater part of the charging movement of said skip.

3. The combination with a concrete mixing machine and its charging skip, of a water tank located on the upper portion of the machine, means for maintaining a practically constant volume of water within said tank, a pipe leading from said tank for carrying a gravity flow of water into the mixing drum of said machine, a valve in said pipe, means adapted to be actuated by said skip during the greater portion of the charging movement thereof for opening said valve to permit the flow of water from the tank into the mixing drum during the greater part of the charging movement of said skip, and a portion of which valve actuating means is adjustable in order to 55 regulate the time interval of the opening movement imparted to said valve.

4. The combination with a concrete mixing machine and its charging skip, of a water tank on the upper portion of said 60 mixing machine and adapted to discharge water by gravity into the mixing drum of the machine, means for maintaining a practically constant volume of water in said tank, a valve in the discharge pipe and adjustable means adapted to be actuated by the skip during the greater portion of the charging movement thereof for opening the valve in said water discharge pipe to permit the flow of water from the tank into the 65 mixing drum during the greater part of the charging movement of said skip.

5. The combination with a concrete mixing machine and its charging skip, of a water tank on the upper portion of said 70 mixing machine, a pipe leading from said tank downwardly into the mixing drum of the machine whereby water may flow by gravity from said tank into said drum, means for maintaining a practically constant head of water in the tank, means adapted to be actuated by the skip during the greater portion of its charging movement for permitting water to flow by gravity during the greater part of the charging 75 movement of the skip through the pipe from the tank into the mixing drum and means associated with said skip-actuated means for controlling the time intervals of the 80 gravity water flow.

In testimony whereof I affix my signature.

WALTER L. STINE.
